Michael Gregory

9869

from Patent

The subject referred to in the letters Patent and making part of the same and claiming a description of the wings of the said Michael Gregory himself of his improvement in the Ice Breaker.

It is known that Michael Gregory of Philadelphia in the County of Philadelphia and State of Pennsylvania has invented a new and useful improvement being a machine for breaking icebergs and other cold navigable ices in the sea. The said machine which is described as follows -
referring first to the upper wing of the ice breaking part of this specification. This machine consists of a boat A of 200 tons strength sufficient to contain and support the machinery required for propelling it and operating the hammer or ice breaker hereafter described and sustaining the shock necessarily produced in passing through thick ice. It is shaped at the bow like a ship or sailing plane B. It is sheathed with iron, having two three or more iron ribs, wings, or guards C well fastened on the upper side and upon which the ice slides as the boat advances, all the upper part of these ironed planes and supported by the same on each side thereof is a concave iron apron D upon which the large pieces of ice are to be broken. These aprons also incline to the right and left and are twisted like a spirally shaped wing for throwing the ice out of the way on each side. Two hammers E. something like a trip hammer each weighing from one to five tons or more of iron are provided for breaking the ice upon the apron. The heads of these hammers ^{more on} ~~are~~ civil labor to be placed over the bow of the boat. The long arm of each hammer moves between guides E. set in a slide F. for throwing the hammer ~~is~~ and out of gear. At the long end of each hammer a friction driving roller G. The hammers are raised by cords H. on the shaft of the propelling wheel which comes in contact with the friction driving roller. The shaft has one or more anchorages to the steam engine or engines in the usual manner and by which the machine is operated. The wheels of the boat are to be made very strong. ~~When~~ ^{the} engine or engines being put in motion the boat is propelled forward.
